Fixture for Drilling Bowling Balls

Henry Hopkins, Detroit, Mich.

Application February 2, 1945, Serial No. 575,917

2 Claims. (Cl. 77—63)

1

The present invention relates to the drilling of bowling balls and specifically to means by the use of which the finger holes may be accurately located and drilled.

Among the objects of the invention is a fixture for application to an ordinary drill press by means of which the ball may be accurately located and held for drilling.

Another object is a fixture which is simple in construction and easy to manipulate to obtain fine adjustments.

Still other objects and advantages will be apparent to those skilled in the art upon reference to the following description and the accompanying drawings in which

Fig. 1 is a plan view of the fixture.

Fig. 2 is a sectional view on line 2—2 of Fig. 1.

Fig. 3 is a side elevation of Fig. 1.

Figs. 4 and 5 are partly sectional views of a ball illustrating the adjustment for drilling.

Figs. 6 and 7 are elevational views of drilled balls showing respectively one and two-finger balls.

As indicated in the drawing, the fixture consists of suitable base 10, preferably of metallic bars welded together to produce a rectangular flat frame and having its opposite sides accurately parallel and rectangular. Upon the base 10 is mounted a wooden frame or seat member 11 provided with a circular ball seat 12 of such dimensions as to allow the ball 13 to be firmly seated therein. After the ball 13 is seated, it is held in position by a second wooden frame 14 also provided with a circular opening of sufficient size to fit well down upon the ball so as to leave a considerable portion projecting above.

The frame 14 is preferably held by a plurality of hinged lag screws 15 having thumb nuts 16 to permit easy and quick application or removal. This ball holding fixture is adapted to be placed upon the table 20 of a conventional drill press and is located thereon by means of a plate 21 fixed near one edge of the table (preferably the front edge) and two side plates 22 spaced sufficiently to allow the frame 10 room to move a short distance in either direction from a centered position. These plates 22 are preferably held in place by tapered pins 23.

The plate 21, at the front of the table 20, is provided with an upwardly extending flat post or plate 24 which has hinged to it a locating finger or indicator 25 so arranged that one face 25A is in alignment with or in a plane with the axis of the drill press spindle, which plane is at right angles to the inner edge of plate 21.

2

With this arrangement, the center line of a ball to be drilled may be accurately aligned with the face 25A and the point or axis of a drill or of a suitable pointed member inserted in the drill chuck in place of the drill. In Fig. 2 there is shown such a pointed member at 26.

With the center line of the ball thus aligned with the drill or point, its forward or back location may be determined by the use of shims 10 such as the one at 27 between the plate 21 and the frame 10, while its lateral position will be determined by the use of shims such as those at 28 between the plates 22 and the sides of frame 10.

15 Figures 4 to 7 illustrate diagrammatically the use of the present invention.

In Fig. 4 a hole A is indicated as having been drilled after replacing the shim 27 with a shim of a thickness to move the center point C of the ball forward of the drill. The hole B was previously drilled with the centerpoint C1 back of the drill, both holes A and B being on the center line as indicated in Fig. 6.

Figs. 5 and 6, the hole D is on the center line 25 but the holes E are laterally displaced therefrom by substituting suitable shims for those at 28.

Now having described the invention and the preferred embodiment thereof, it is to be understood that the invention is to be limited, not to the specific details herein set forth, but only by the scope of the claims which follow.

I claim:

1. In combination with the table of a drill press a rectangular frame seated on said table and provided with a centrally located ball seat, a locating plate at the front of said table adapted to position said frame in a forward and back direction, said plate having its inner edge at right angles to the axis of the spindle of said press, 35 locating plates at the sides of said table and adapted to position said frame in a lateral direction, and an arm hinged to the first locating plate and movable in that plane including the axis of the press spindle and perpendicular to said first plate.

2. In combination with the table of a drill press a rectangular frame seated on said table and provided with a centrally located ball seat, a locating plate at the front of said table adapted to 50 position said frame in a forward and back direction, said plate having its inner edge at right angles to the axis of the spindle of said press, locating plates at the sides of said table and adapted to position said frame in a lateral direction, and an arm hinged to the first locating plate 55

and movable in that plane including the axis of the press spindle and perpendicular to said first plate, one side face of said arm being plane and in accurate alignment with said axis.

HENRY HOPKINS.
